Primary Examiner — Austin Murphy(74) *Attorney, Agent, or Firm* — Knobbe Martens Olson & Bear LLP(57) **CLAIM**

The ornamental designs for the angle grinders, as shown and described.

DESCRIPTION

FIG. 1 is a top, front and left side perspective view of an angle grinder that is arranged and configured in accordance with a preferred embodiment;

FIG. 2 is a left side view of the angle grinder of FIG. 1;

FIG. 3 is a top view of the angle grinder of FIG. 1;

FIG. 4 is a bottom view of the angle grinder of FIG. 1;

FIG. 5 is a right side view of the angle grinder of FIG. 1;

FIG. 6 is a front view of the angle grinder of FIG. 1;

FIG. 7 is a top, front and left side perspective view of an angle grinder that is arranged and configured in accordance with another preferred embodiment;

FIG. 8 is a front view of the angle grinder of FIG. 7;

FIG. 9 is a top view of the angle grinder of FIG. 7;

FIG. 10 is a bottom view of the angle grinder of FIG. 7;

FIG. 11 is a left side view of the angle grinder of FIG. 7; and,

FIG. 12 is a right side view of the angle grinder of FIG. 7. Where utilized, the broken lines show portions of the angle grinders that form no part of the claimed design.
